UNITED STATES PATENT OFFICE

EDWARD W. MILLER, OF SPRINGFIELD, VERMONT, ASSIGNOR TO THE FELLOWS GEAR SHAPER COMPANY, OF SPRINGFIELD, VERMONT, A CORPORATION OF VERMONT

TRUING MEANS FOR FORMED GEAR GRINDING WHEELS

Application filed September 17, 1929. Serial No. 393,994.

This invention relates to the art of finishing gear teeth by grinding with the use of a grinding wheel having a formed grinding surface which imparts a complementary or 5 counterpart form to the faces of the gear teeth. It is primarily concerned with means for dressing the grinding wheel to give its active face the desired form; and further concerned, among other things, with means 10 associated with the foregoing for locating the formed face of the wheel in a given relation to the work. Gear finishing machines of the type above referred to have long been known, but those heretofore used for finishing involute gear teeth have been incapable of giving 15 perfect satisfaction, due to lack of practical means for making a sufficiently true involute profile in the grinding wheel face to finish involute gear teeth with the desired 20 perfection of accuracy. Meshing gear teeth which are not true within narrow limits of accuracy make an objectionable noise in running.

It has been my object to provide grinding 25 wheels for machines of the type indicated having grinding or active faces of true involute profile, and to provide a truing or dressing means capable of initially forming such profile, and maintaining it, with an exact 30 and accurate involute curvature corresponding to the involute from any desired base circle. A further object has been to locate the active face on the wheel in a position such that it is rather a part of the periphery than 35 of the end face of the wheel. In accomplishing these objects I have provided a truing apparatus in which the truing tool is caused to move in a path conforming to that of a given point in an inextensible cord being 40 wrapped about or unwrapped from a cylindrical surface; and in the preferred embodiment of which the apparatus is mounted on the grinding machine so that the path of the tool is in the prolongation of one of the tooth 45 faces of the work piece. The invention consists in the means and combinations described in the following specification for carrying the foregoing objects into effect, together with equivalents thereof and the principles 50 of means embodied therein and compre-

hended within the scope of the following claims.

In the drawings herewith,—

Fig. 1 is a front elevation of a gear grinding machine having my improved truing 55 means in operative association with the grinding wheel;

Fig. 2 is a plan view of the machine;

Fig. 3 is a fragmentary longitudinal section taken on line 3—3 of Fig. 2, and showing 60 the work holding and indexing means of the machine;

Fig. 4 is a fragmentary end elevation as seen from the left of Figs. 1 and 2 represented on a larger scale; 65

Fig. 5 is a cross section of the truing means taken on line 5—5 of Fig. 2 and shown on a larger scale;

Fig. 6 is a longitudinal section of the truing means taken on line 6—6 of Fig. 4 and 70 enlarged;

Fig. 7 is a fragmentary cross section taken on line 7—7 of Figs. 1 and 6;

Fig. 8 is a view similar to Fig. 5 but showing the truing means in a different position; 75

Fig. 9 is a diagrammatic view illustrating the characteristic principles of the coating elements which control the movement of the truing tool;

Fig. 10 is a cross section on line 10—10 of 80 Fig. 6;

Fig. 11 is a fragmentary elevation showing the relationship of the work and grinding wheel when in operation;

Figs. 12 and 13 are detail views of the truing tool holder and means for shifting and adjusting it. 85

The machine comprises a base 1 on which is a slide 2 movable to right and left (with respect to Figs. 1 and 2) on ways 3 (Fig. 4); being so moved by a crank 4 and a connecting rod 5, shaft 6 and belt pulley 7, as may be plainly understood from the drawings without further explanation. The slide 2 carries an indexing head or fixture 8 and a support or fixture 9 for the truing mechanism. These fixtures hold centers 10 and 11 by which is supported an arbor 12 having clamped thereon the work piece 13, a gear which has been previously cut and of which the tooth faces 100

are to be finished by grinding. The center 10 in the indexing head 8 is secured in a hollow shaft 14 which is rotatable in the head and carries a crank 15 and index disk 16, the latter having a circular series of holes adapted to be engaged singly by a locking pin 17, as shown in Fig. 3, and having lugs 18 engaging a dog 19 secured to the work carrying arbor 12.

10 Rising from the machine base beside and above the slide 2 is a head 20 having bearings 21 in which is mounted a horizontal shaft carrying the grinding wheel 22 and a driving belt pulley 23. The grinding wheel 15 overhangs the work carrying slide and is located "off center" with respect to the work, by which I mean that it is at one side of the vertical plane through the axis of the work, and of the supporting centers thereof. More 20 broadly stated, the wheel is at one side of the plane which passes through the axis of the work and perpendicular to the axis of the wheel. This relationship is shown in Figs. 4, 7 and 11. The grinding wheel is 25 designed to act on only one side of one tooth at a time, and to that end has a grinding face or active surface 24 adjacent to its periphery and at the side of the latter away from the vertical plane through the work axis. In 30 other words, the grinding wheel, instead of being radial to the work (in a plane containing the axis of the work) is in a plane at one side of and parallel to such axis, and its active face is at the side away from the parallel axial plane of the work. It is thus set over as far as it may be without causing interference with the adjacent side of the next tooth, in order that the character of grinding which it performs may approximate what is 40 called peripheral grinding rather than face grinding, and that the reaction of the grinding thrust have as large a component radial to the wheel as possible and the minimum possible component axially of the wheel. 45 This arrangement affords greater wheel clearance, tends toward greater accuracy of grinding effect on the work, and gives a better control of the position and running of the wheel than is possible with a radially arranged wheel.

In order to grind correctly the faces of involute gear teeth, the active face 24 of the grinding wheel must have a true involute curve in profile, that is, in planes radial to the wheel. In order to produce such curvature with truth and accuracy, I have devised an attachment, carrying a truing tool of suitable character and having means for traversing the point of such truing tool in a curved path, the curve of which is a true involute of the base circle of the gear being ground and is located in a radial plane of the wheel. Fig. 11 shows a work piece 13 having teeth 25, the face curves 26 of which are involutes 60 of the base circle 27 represented by broken

lines. The problem which I have successfully solved by this invention has been to effect traverse of the truing tool across the grinding wheel face 24 in a path which is likewise an involute of the same base circle. The means for effecting the desired result are as follows.

The fixture 9 has two separated uprights 28 and 29 in which is fixed immovably the bar 11, the end of which provides the fixed center previously described. On the bar 11 between the uprights are fastened sleeves 30 and 31 having flanges at their remoter ends formed with external cylindrical surfaces 32 and 33 of the same, or approximately the same, diameter as the base circle of the gear being ground. Between these sleeves there is fixed on the bar a projection 34 having an involute face 35.

A rockable holder embraces the above named sleeves and projection and carries the truing tool. Said holder comprises a substantially cylindrical shell 36 and annular end plates or heads 37 and 38 secured to the ends of the shell, the latter being of such length that the end plates, which overlap at their inner circumferences the flanges of sleeves 30 and 31, have a bearing on the outer end surfaces of such flanges to maintain the holder in position axially of the sleeves. Plates or bars 39 and 40 having straight and plane surfaces 41 and 42, respectively, are secured to the inner sides of the heads 37 and 38 and engage the cylindrical surfaces 32 and 33 respectively. The surfaces 41 and 42 are in the same plane.

In one side of the holder is an offset 43 providing a chamber in which is located a bar 44 mounted on a pivot 45 and having a projection 46 with a plane surface 47 overlapping the projection 34 and bearing on the curved surface 35 of the latter. Screws 48 and 49 are fitted in opposite walls of the offset 43 and bear on the bar 44 to adjust the latter angularly about its pivot. A cover 50 is secured over the end of the offset and carries a handle 51 by which the holder may be manually rocked. Limits to the rocking movement are set by a projection 52 on the holder located between fixed stops or abutments 53 and 54 on the base part of the head 9 and on the upright 38 thereof. The truing tool 55, which may be a diamond or the like such as is commonly used for truing abrasive wheels, is set in the end of a shank 56 which in turn projects from the side of the terminal head 57 of a shaft 58 which is mounted to fit closely but rotatably in a sleeve 59 projecting in the axial direction from the head plate 38 of the holder. Said sleeve projects to such a distance as necessary to locate the truing tool in the same vertical plane with the axis of the grinding wheel when the slide 2 is in one of its possible positions, and while the main portion of the holder is 125 130

far enough away from the wheel to be clear of it. In other words, the arrangement is such that the truing tool may be placed where its arc of travel is in a radial plane of the wheel, so that it may form the profile of the active grinding face in a radial plane. Preferably the truing tool is caused to occupy this position when the carrier slide 2 is at one limit of its travel, for instance, as shown in Fig. 1, in order to facilitate correct placement of the tool.

The point of the truing tool is located in the same plane with the surfaces 41 and 42, and may be fixed immovably in this plane, but preferably is arranged with capacity for independent rotation, as previously stated, for the purpose of accurate adjustment, and for another purpose, later explained. By virtue of its location in this plane, the rocking of the holder causes it to travel in an involute curve because the surfaces 41 and 42 then roll upon the cylindrical surfaces 32 and 33.

The overlapping projections 34 and 46, and the means for adjusting the latter, are provided in order to prevent uncontrolled slip of the rocking holder on the cylinders 32, 33, and also to permit of variation, within limits, of the actual base circle with respect to which the path of the truing tool is developed. Owing to the steep inclination of the plane surfaces 41 and 42, which results from the offset location of the grinding wheel it is possible to locate the projection 34 directly under the projection 46 and utilize gravity as the sole means for holding the coacting surfaces of these projections in engagement, which is of advantage from the standpoint of simplicity. These projections constitute in effect the mating teeth of a single toothed involute rack and gear couple, of which the plane established by the surfaces 41 and 42 is the pitch plane. The plane face 47 of the rack tooth 46 may have any desired inclination, within practicable limits, to the pitch plane. The base circle for the involute face 35 of projection 34 is determined according to well known principles of involute gear design, as shown by the diagram in Fig. 9, thus: From the pitch point 60, which is the intersection between the pitch plane 42, the radius 61 of the work axis perpendicular to such plane, and the face 47 of the rack tooth when the latter is in neutral position, a line 62 is laid out perpendicular to the rack tooth face. The circle 63 drawn tangent to the line 62 with the work axis as the center is the base circle with respect to which the involute curve 35 is developed. With the relationship existing as thus defined, rocking of the holder produces a rolling effect between the cylinders 32, 33 and plane surfaces 41, 42, without slip, and the truing tool is caused to describe a curve which is a true and accurate involute of the cylinders 32 and 33. When the tool is

thus moved in the perpendicular plane containing the axis of the grinding wheel, and the latter is rotated at the same time, the tool causes a surface of revolution to be generated in the grinding wheel which in profile is a true involute to the desired base circle. Wherever the wheel may be located as to the height of its axis or along the line of its axis (within practicable limits of course), the truing tool forms the active surface complementary to the desired tooth form and in the location relative to the work axis which will cause the teeth of the work piece to be ground off true and accurately.

Angular adjustment of the rack tooth by means of the screws 48 and 49 enables an accurate setting to be made in case after a trial grinding the pressure angle of the ground gear tooth is found to be incorrect. It also enables the truing tool to describe an involute to a base circle slightly larger or smaller than the cylinders 32 and 33, since a change in the inclination of the rack tooth face 47 will cause the pitch point to lie elsewhere than in the pitch plane 42; that is, to one side or the other of such pitch plane according to the direction in which the inclination is shifted. Then when the tool holder is rocked, it will be moved at a rate proportional to the greater or less distance of the new pitch point from the axis, with some incidental slippage of the surfaces 41 and 42 on the cylinders 32 and 33, but with the result of causing the truing tool to describe accurately an involute to a different base cylinder. For wider variations than are permitted by this adjustment, other holders and accessory parts, or complete alternative fixtures may be substituted.

It sometimes happens that the roots of gear teeth are located within the base circle. This condition is illustrated in Fig. 11. Although only the part of the tooth face outside of the base circle is an active working face, nevertheless it is desirable to grind the tooth inward substantially to its root in order that no stock may be left which might injure the points of mating teeth. Accordingly the grinding wheel extends approximately to the root circumference of the gear, and I have made the truing tool effective to dress the active face of the wheel beyond the limit of the involute curvature by mounting the tool rotatably in the holding sleeve 59 and by providing an outstanding arm or finger 64 adapted to be turned manually when the carrier has been rocked to the position where the truing tool is in the prolongation of the base cylinder, this location being determined by contact of the stops 52 and 53. The extended curve then generated is the arc of a circle tangent to the involute curve and extending to the outermost edge of the active face. The character of this extended curvature is not important, provided only that

the wheel is enabled to continue the tooth face curves smoothly to the tooth root.

A stop finger 65 protrudes from the supporting sleeve beside the tool carrying head 57 to arrest the arm 64 at the limit of its forward movement. Another arm or bracket 66 projecting from the sleeve carries an adjustable stop screw 67 which engages the arm 64 and arrests it when the truing tool is brought into the plane of surfaces 41, 42, or other pitch plane established by adjustment of the rack tooth face 47, previously described.

It will be readily understood that the operation of the machine carries the work piece back and forth across the formed face of the grinding wheel, which latter gives the prescribed shape to the tooth. After each tooth has been ground, the work is indexed; and when all have been ground on one side the work piece is removed from the arbor and replaced in reverse position.

From time to time, as often as desired, and when the work carriage is in the proper position, the truing tool is rocked to restore the grinding wheel face to true form. It may be understood without detailed explanation that adjusting means of a character well known in grinding machines may be provided in this machine for adjusting the wheel either in the axial direction, or vertically, or in both directions to maintain its active face in the correct working position after repeated grinding and truing actions.

The relation of the truing means to the work holding means, by virtue of which the tool holder is rocked about the axis of the work piece and the tool itself caused to generate an involute to the base circle of the work in the exact location occupied by the tooth face next to be ground, is an important factor in insuring accuracy of result. It also enables a depth feed or increased cut to be made by shifting the work piece circumferentially through a small angle. However, although I claim all novelty and advantage in this feature, my invention is not specifically limited thereto, but includes all novel features in the truing fixture itself independently of its association with the work holding and carrying means of the machine. A truing fixture substantially like that here described may be used apart from a gear grinding machine, for the purposes and in the manner described, with satisfaction as to results, although without the same ease and simplicity as in an association such as here illustrated.

It will be understood also that the same principles may be embodied in other constructions and arrangements of a machine and its parts than that here illustrated. For instance, the steep inclination of the rolling plane 41-42 here shown is important only as a means for effecting the desired "off center" formation of the grinding wheel. If

it is preferred to arrange the wheel more nearly, or exactly, in a radial plane of the work, the rocking holder may be placed so that its planes are more nearly horizontal, and the projection 34 correspondingly re-located. These principles may be applied to a completely automatic machine in which the indexing of the work and the rocking of the truing means are performed automatically. I have shown here only provisions for manually performing these functions in the interest of simplicity and clearness, and because the new principles of the invention are thus adequately disclosed.

What I claim and desire to secure by Letters Patent is:

1. In a gear grinding machine, the combination with a work supporting center, of a cylinder coaxial with said center having an external surface substantially the same in diameter as the base circle of the prescribed involute curve of the gear tooth faces to be ground, a rockable holder having a plane surface engaging said cylindrical surface and adapted to rock thereon, a truing tool carried by said holder and located in the same plane with said plane surface, and overlapping projections, one of which is fixed with respect to said cylinder and the other is secured to the rocking holder, said projections having engaging surfaces formed correspondingly to the mating tooth surfaces of a rack and gear couple of which the pitch line coincides with said plane surface.

2. A truing mechanism for forming an involute profile in a grinding wheel comprising a stationary support having an exterior cylindrical surface, a rockable holder having a plane surface bearing on said cylindrical surface, a truing tool carried by said holder and located in the same plane with said plane surface, a stationary projection having an involute curved surface crossing said cylindrical surface, and a coacting projection carried by said holder and having a plane face crossing the first named plane surface, the faces of said projections being in contact with one another and having the same relation as the mating faces of an involute gear and rack couple of which the pitch line coincides with the first named plane surface.

3. A truing mechanism for forming an involute profile in a grinding wheel comprising a stationary support having an exterior cylindrical surface, a rockable holder having a plane surface bearing on said cylindrical surface, a truing tool carried by said holder and located in the same plane with said plane surface, a stationary projection having an involute curved surface crossing said cylindrical surface, a coacting projection carried by said holder and having a plane face crossing the first named plane surface, the faces of said projections being in contact with one

another and having the same relation as the mating faces of an involute gear and rack couple of which the pitch line coincides with the first named plane surface, and means for 5 adjusting the last named projection so as to alter the angle which its plane face makes with the first named plane surface, whereby to shift the location of the actual pitch line of the projections.

10 4. A grinding wheel truing mechanism comprising a relatively stationary support including a convex cylindrical surface and a projection having a curved face crossing the said surface, said curved face being an involute to a base circle concentric with said cylindrical surface, a rockable holder having a plane surface contacting and bearing on said cylindrical surface and adapted to rock thereon, a projection pivoted on said holder 15 having a plane face crossing the plane of the before named plane surface and adapted to bear on the curved face of the first projection, means for adjusting said projection about its axis to vary the angle which its face 20 makes with said plane surface, and a truing tool carried by said holder in the same plane with the before named plane surface.

25 5. A truing mechanism for forming an involute profile in a grinding wheel comprising a rockable tool holder having a plane contact surface, a cylindrical supporting surface with which said plane surface has rocking engagement, coaxing involute rack and pinion teeth, the rack tooth of which is carried by said holder and the pinion tooth secured to said support, and the pitch line of 30 which teeth substantially coincides with the plane of said plane surface, and means for adjusting the rack tooth angularly about an axis parallel to the axis of said cylindrical surface, whereby to shift the pitch line of 35 said teeth to either side away from and toward the said plane.

40 In testimony whereof I have affixed my
45 signature.

EDWARD W. MILLER.
